ANNUNCIATOR CONSTRUCTION

Christian Miller, New York, N. Y., assignor to
 Edwards and Company, Inc., a corporation of
 New York

Application March 7, 1932, Serial No. 597,133

10 Claims. (Cl. 177—326)

This invention relates to signaling apparatus and more particularly to visual and audible signaling devices such as are more commonly called "annunciators".

One of the objects of this invention is to provide a construction of the above-mentioned character that will be simple, inexpensive, compact, and of dependable and reliable action in practical use. Another object is to provide an apparatus of the above-mentioned character which is capable of rapid assembly, easily and quickly installed and the parts of which are quickly and readily accessible for replacement or repair.

Another object of this invention is to provide an annunciator construction which may be dependably and inexpensively installed in a suitable recess in a wall and more particularly to provide such a construction which will leave the wall and hence the room devoid of ugly or unsightly projecting parts. Another object is to provide an annunciator construction which can be progressively installed as the building construction itself proceeds and approaches completion. Another object is to provide a construction of the above-mentioned character in which precision of installation and variations in the building or wall construction itself need not be coped with while at the same time achieving low cost and efficiency of installation and compactness of construction and neatness of appearance. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which is shown a preferred embodiment of my invention,

Figure 1 is a front view of the apparatus as installed in the wall of a room;

Figure 2 is a vertical central sectional view on an enlarged scale, as seen along the line 2—2 of Figure 1;

Figure 3 is a horizontal sectional view, as seen along the line 3—3 of Figure 2;

Figure 4 is an exploded perspective view of a single signaling unit;

Figure 5 is a fragmentary perspective view of a portion of the back wall of the supporting frame shown in Figures 2 and 3, showing one of the guides or supports for a restoring device;

Figure 6 is a perspective view of part of the signal-restoring mechanism, where the signal

units are arranged in two gangs or two vertically displaced rows;

Figure 7 is a fragmentary front elevation of the lower left-hand corner portion of the frame, more particularly as seen along the line 7—7 of Figure 3, and

Figure 8 is a fragmentary end elevation, more particularly as seen along the line 8—8 of Figure 3.

Similar reference characters refer to similar parts throughout the several views of the drawings.

Referring again to the drawings and more particularly to Figures 1, 2 and 3, I have generally indicated at 10 a wall of any suitable or usual construction employed in building interiors and in this wall I form, in any suitable way, a suitable recess generally rectangular in shape and of suitable depth; this recess is generally indicated at 11 (Figures 2 and 3) and is preferably formed in the wall before the plastering has been completed. In the bottom of this recess I secure, in any suitable manner, a strut 12 preferably of wood or, the part 12 may be considered to represent part of the woodwork embodied in the wall in case a wall embodying wooden members is employed.

The recess 11 is substantially rectangular and its length and breadth as well as depth are so proportioned that a sheet metal outlet box generally indicated at 13 may be received therein; the box 13 has its bottom wall 13a (Figures 2 and 3) provided with suitable openings to receive screws 14 which are threaded into the strut 12, thus to securely hold the box 13 in place.

The box 13 is provided with suitably positioned knock-outs 15, one of which is shown in Figure 2 as having been removed so as to permit the cable that is strung through the conduit buried or concealed in the wall to be passed into the box 13 and the conductors thereof connected, in a manner described hereinafter, to the signaling apparatus housed within the box 13.

The box 13 is made of a suitably heavy sheet metal and its side walls 13b and 13c (Figure 3) are bent over and inwardly to form vertically extending flanges 13k and 13d, respectively. Its upper and lower walls 13e and 13f (Figure 2) terminate preferably in the plane of the flanges 13k and 13d and they may, if desired, be flanged or they may be left plain.

I then provide a frame or main support generally indicated at 16 (Figures 2 and 3) and preferably made of a suitably heavy sheet metal; it is bent or stamped into an inverted U-shaped

form, as viewed in Figure 3, to provide a main back wall 16^a, side walls 16^b and 16^c, and flanges 16^d and 16^e. The horizontal length of the side walls 16^b and 16^c, as viewed in Figure 3, is somewhat less than the depth of the outlet box 13 so as to provide adequate space between the walls 16^a and 13^a (Figure 3) for leading in the conduit and conductors should it be necessary to use a knock-out in the back wall 13^a of the box 13. Similarly, the horizontal spacing between the side walls 16^b and 16^c of the main frame 16 is such that there is provided adequate space between the side wall member 13^b (of the box 13) and 16^b (of the frame 16) and between the side wall members 16^c and 13^c for the entry of conduit and cable should circumstances dictate the use of a knock-out in either or both of the side walls 13^b and 13^c of the box 13.

As is better shown in Figure 2, the vertical dimension of the sheet metal frame 16 is also preferably less than the vertical dimension of the box 13, thus to provide also adequate space above and below the frame 16 and the parts carried by it for the accommodation of the conduit ends and conductors should it be necessary to use one or more knock-outs in the upper or lower walls 13^e and 13^f of the box 13.

The flanges 16^d and 16^e of the main frame 16 (Figure 3) will be seen to extend laterally somewhat considerably beyond the side walls 13^b and 13^c of the box 13. This is an important feature, as will be more clearly pointed out hereinafter; suffice it at this point to point out, however, that, after the box 13 has been installed in the recess 11 as above noted, the plaster or like finish of the wall may be applied, as is indicated at 17 in Figures 2 and 3. Thereafter the frame 16, with the parts, all as described hereinafter, is inserted into the box 13 whence the flanges 40 16^d and 16^e (Figure 3) overlap and rest against the finished wall, more particularly against the plaster 17 if plaster is used for the finish, all as is clearly shown in Figure 3.

The frame 16 is then secured in place by a suitable number of screws, preferably four in number but only two of which are shown at 18 and 19 in Figure 3; the screws 18, 19, etc. pass through inclined or arcuate slots 20 (see Figure 7) provided in the flanges 16^d and 16^e and are threaded into suitable threaded openings provided in the box flanges 13^c and 13^d (Figure 3).

The arcuate or inclined slots 20 (Figure 7) permit the frame 16 to be tilted or swung about a horizontal axis and thus adjusted into a truly horizontal position, the flanges 16^d and 16^e, projecting beyond the finished wall surface 17, permit the application of a spirit level or the like to assure accuracy of horizontal position of the frame 16; the screws 18, 19, etc. may then be driven home or tightened up, the flanges 16^d and 16^e, furthermore, being virtually held in the plane of the finished wall surface 17 against which they abut, thus bringing the back wall 16^a of the frame 16 and related parts carried by the frame, into exact parallelism with the plane of the finished wall 17. These features are important as will be further pointed out hereinafter.

The frame 16, particularly the back wall 16^a thereof, carries a plurality of signaling units 70 which, depending upon the particular practical requirements and hence upon the size of the outlet box and the frame, may be of any suitable number and disposed in any suitable number of vertical and horizontal rows. Illustratively, I have provided two vertically displaced hori-

zontal rows of signaling units and in Figure 2 will be seen a signaling unit 21 of the upper row and a signaling unit 22 of the lower row. These signaling units are of identical construction and hence it will suffice to describe in detail only one of them.

Accordingly, turning now to Figure 4, I first provide a sheet metal frame generally indicated at 23 and preferably made of magnetic material such as sheet steel or sheet iron and bend it so as to provide a vertically extending plate 23^a and a horizontally extending plate 23^b, the latter being provided with horizontally spaced upstanding arms 23^c and 23^d punched or stamped out to provide upper apertures or bearings 23^e and lower apertures or bearings 23^f (only one of the latter being visible in Figure 4).

Extending above and parallel to the horizontal portion 23^b of the frame 23 is an electromagnet generally indicated at 24; the latter comprises a winding 25 about a core 26 of magnetic material and extending between end insulating members 27 and 28, the latter being preferably substantially square in shape. Core 26 extends through a suitable opening in the plate portion 23^a where it is riveted over or otherwise secured in place, thus holding the electromagnet 24 in position.

Still referring to Figure 4, it will be seen that I provide an armature generally indicated at 29 adapted to be actuated by the electromagnet 24 and to form part of the magnetic circuit of which the core 26 and the frame 23 form parts. Armature 29 is made of sheet metal of suitable magnetic characteristics and is provided at its upper end with two ears 29^a and 29^b through which extends a pin 30 held against displacement or dislodgment therefrom by any suitable means such as by flattening out the pin 30 as at 30^a and 30^b, within and adjacent to the ears 29^a and 29^b. Thus, there are provided two projecting portions or trunnions 30^c and 30^d adapted to be received in the bearings 23^e of the upstanding arms 23^c and 23^d, the latter being sprung or bent apart to receive the trunnions and then returned to normal position.

Armature 29 is thus pivotally mounted to swing, in depending relation, toward or away from the left-hand end of the magnet core 26; it is normally held in a position away from the armature core by a leaf spring 33 preferably of bronze or other suitable substantially non-magnetic spring material so that its lower end, which has a transversely extending opening or slot 33^a, may coact with the so-called annunciator "drop" 31, in a manner described in detail below.

The annunciator drop 31 is of sheet metal construction and includes a portion 31^a and a portion 31^b extending substantially at right angles to each other; portion 31^a is provided with two upstanding ears 31^c and 31^d which are apertured as shown in Figure 4 and are adapted to be received between the lower left-hand portions of the arms 23^c and 23^d, the apertures being alined with the bearing openings 23^e to receive a pin or rivet 32 (Figure 2); thus the "drop" 31 is pivotally supported by the frame 23 to swing from the position shown in Figure 4 to a position substantially like that shown in Figure 2 with respect to the signaling unit 21.

Intermediate of the ears 31^c and 31^d (Figure 4) 70 the member 31 is provided with an upstanding lug 31^e which has at its upper end a tongue 31^f adapted, when the member 31 is swung in clockwise direction as viewed in Figure 4, to ride down along the left-hand face of the armature 29 and 75

to be received within the slot 28^c of the latter as the armature 29 is pressed in clockwise direction by the spring 33.

When the "drop" 31 is thus swung into uppermost position, as shown in the upper part of Figure 2, it is held in that position by the coaction of the latch member 31^d and the armature 29, but as soon as the magnet 24 is energized armature 29 is swung in counter-clockwise direction, the latching tongue 31^e is disengaged from the armature 21, and the drop 31 is free to drop or swing in counter-clockwise direction, thus to display, in a manner more clearly described hereinafter, a suitable call indicia such as a number 15 or designation or the like that is to indicate the origin of the closure of the circuit of the magnet. For this purpose, the part 31^k of the drop 31 is suitably flanged to receive preferably removably a 20 suitably shaped card bearing the number, name, or other indicia that may be employed. These flanges for holding the indicator card extend preferably at the two sides and across the bottom of the part 31^k of the drop 31 and are indicated in Figures 4 and 2 at 31^l.

Referring now again to Figure 4, the back or vertical plate portion 23^a in the frame 23 is provided with openings preferably two in number, as shown at 34 and 35, so that the assembled signaling unit may be secured in place to the back wall 16^a of the frame 16, as by screws 36 (Figure 2). Any suitable number of signaling units may thus be secured to the back wall 16^a and they are preferably arranged in suitable horizontal and vertical rows. In Figure 2 there are shown two such units 21 and 22 each being one of several arranged and aligned horizontally. The device 21 (Figure 2) may be considered to be one of several arranged in the upper horizontal row and the device 22 typifies one of several arranged in another and lower horizontal row. Thus, the drops 31 of all of the units are nicely aligned. Normally all of the drops 31 are held in the position of the drop 31 as shown in connection with the signaling unit 21 of Figure 2, by their respective latch and armature members 31^d and 29 (Figure 4).

The horizontal portion 23^b of the frame 23, moreover, is provided at its left-hand end with an upwardly bent tongue 23^c (Figure 2) positioned in the path of downward movement of the portion 31^a of the drop 31 as the latter swings in counter-clockwise direction about its pivoting pin 32, the parts being so proportioned that the fall of the drop 31 is halted at such a point that the indicator-card-bearing portion 31^k comes to rest in a horizontal position, as is shown in connection with the unit 22 of Figure 2, thus to display the indicator card and hold it in a vertical plane so that it may be easily read or visually identified when viewed from the left in Figure 2 or in Figure 4.

Suitable means are provided for restoring the actuated drop or drops to uppermost or latching position but inasmuch as the preferred form of restoring means coacts in a unique way with certain other features of my invention, such other features will first be described in detail.

Accordingly, it is first to be recalled, referring now to Figure 3, how, irrespective of any misalignment in the mounting or positioning of the wall box 13, the frame 16, when secured to the wall box 13, may be aligned into true horizontal position, thus to align all of the drops into true horizontal position, and how also the front flanges

16^d and 16^e of the frame 16, referring still to Figure 3, overlap the plastered or finished wall portions 17, thus in turn to bring the plane of the indicator cards on the drops, when the latter are all actuated, into exact parallelism with the plane 5 of the finished wall. After these parts have thus been mounted, and it will be noted how speedily this alignment and accurate mounting may be achieved, a finish or cover plate 36 (Figures 1, 2 and 3) is ready to be placed in position. 10

This cover plate 36, which embodies certain other features fully described hereinafter, is preferably made of a suitable sheet metal and may be given any desired exterior finish which may or may not match the finish of the wall or which 15 may be of a character to give an appropriate contrast with the finish of the wall.

The plate 36 is of sufficient vertical and horizontal dimension to extend preferably well above and below the upper and lower walls of the box 20 13 (see Figure 2) and is of sufficient horizontal dimension to extend beyond and overlap the flanges 16^d and 16^e (see now Figure 3) of the frame 16. Preferably, the cover plate 36 has a peripherally extending flange 36^a (Figures 2 and 25 3) which is adapted to rest against the finished wall portion 17 whether the latter is plaster or of any other construction.

As appears better in Figure 1, the finishing plate 36 is provided with suitable openings 30 preferably four in number and preferably countersunk adapted to receive screws 37 which are threaded into correspondingly spaced openings 38 (see Figure 7) in the flanges 16^d and 16^e of the frame 16, thus to secure the cover plate 36 35 in place and to draw it and its peripheral flange 36^a snugly against the finished wall portion 17 and thus to seal the installation against access to the various apparatus of dust, dirt, and other foreign material. 40

The four screw holes 38 in the flanges 16^d and 16^e (Figure 7) are appropriately aligned so that, when the frame 16 itself is leveled off, the subsequent attachment of the cover 36 insures that the latter likewise assumes a position with its horizontal and vertical edges properly aligned respectively with the horizontal and vertical, a feature of importance in insuring a neat and proper appearance. 45

The cover plate 36 (Figures 1 and 2) is punched 50 out to provide horizontally extending slots which in number correspond to the number of horizontal rows of signaling units carried by the frame 16. Thus, in the illustrative embodiment shown in the drawings, where I have provided two horizontal rows of signaling units, the cover plate 36 is given two horizontal slots 36^b and 36^c (Figures 1 and 2) one for each row of signaling units. 55

These slots are virtually windows and have a vertical dimension substantially equivalent to 60 the vertical dimension of the indicator card carried by the drops. The length of the slots depends, of course, upon the number of signaling units that are arranged in the row or rows. Moreover, the windows or slots are positioned, as 65 is better shown in Figure 2, so that when a drop is actuated and moved into the position of the drop of the unit 22, the indicator card carried thereby is positioned directly adjacent the slot, the card being otherwise invisible when the drop 70 is in its upper or restored position.

Upon the interior of the cover plate 36 and extending over the slot or slots is a suitable sheet 75 39 of transparent material, such as glass, held in place by any suitable means, such as sheet metal

end straps 40 which are preferably spot-welded to the inside face of the cover 36.

Purely by way of illustration, I might note that, by reason of certain features of my invention, I am enabled to achieve such compactness of construction that the vertical dimension of the window or slot above-mentioned can be as small as one-half inch and its horizontal dimension equivalent to about one inch or less per signaling unit. If, for example, there are three signaling units arranged in a single horizontal row, the length or horizontal dimension of the window need not be greater than three inches.

Underneath the window or windows and preferably intermediate of the vertical side edges of the cover plate 36, the latter is provided with a round opening stamped to provide a cylindrical guiding flange 36^a to slidably receive a cylindrical push button 41 (Figures 1, 2 and 3). The push button 41 is mounted, as is better shown in Figure 2, upon the left-hand end of a heavy sheet metal member 42 whose right-hand end is reduced as at 42^a to be slidably received in a suitably shaped opening 43 (see Figure 5) formed in the vertical portion 44^a of a bracket member 44 which, as is better shown in Figure 5, is preferably formed by stamping a tongue or strip out of the back wall 16^a of the frame 16 and bending it into the shape shown in Figures 2 and 5.

The parts 41—42 (Figure 2) are thus dependably supported and guided for movement in a horizontal direction by the front plate 36 and by the bracket 44; a cotter pin 45 or the like extends through the right-hand end of portion 42^a (see Figure 2) to prevent disengagement of the member 42 from the bracket 44, the pin 45, moreover, also acting as a stop to limit the movement of the parts 41—42 in a direction toward the left, as viewed in Figure 2, under the action of a spring 46 which extends about the portion 42^a and between the bracket portion 44^a and a shouldered part 42^b of the member 42. The spring thus also normally holds the push button 41 in its projected position as is better shown in Figures 2 and 3.

The left-hand portion of the member 42 (Figure 2) is stamped or shaped to provide a cam portion 42^c which coacts with certain other parts to cause the actuated drop or drops to be restored when the button 41 is moved to the right as viewed in Figure 2.

Considering now the parts which are actuated by the cam portion 42^c, I provide a restoring member for each of the vertically displaced rows of signaling units; thus where I employ two such rows of units, I provide two restoring members which are better shown, in detached perspective, in Figure 6, wherein the member 46 is adapted to restore the drops of the signaling units 22 in the lower row and the member 47 is adapted to function similarly with respect to the drops of the upper row of signaling units 21.

These members are made of a suitably heavy strap metal and are substantially U-shaped, having therefore side arm portions 46^a and 46^b for the member 46 and side arm portions 47^a and 47^b for the member 47. These side arm portions are bent at their ends substantially as is shown in Figure 6 and are preferably cut down to form trunnions or pivots 48 which are loosely received in openings 49 suitably positioned and formed in the side portions 16^b and 16^c (Figures 3 and 2) of the frame 16, these openings being so positioned with respect to the rows of signaling units that, when the restoring members 46, 47, etc. assume and retain their normal horizontal posi-

tions, as is better shown in Figure 2, the main portions thereof extend virtually in the path of downward swinging movement of any of the drops of the signaling units. Note, for example, in Figure 2, how the member 46 extends underneath and crosswise of the actuated drop 31 of the signaling unit 22.

If the pivotally mounted restoring members 46, 47, etc. are swung in clockwise direction as viewed in Figures 2 and 6, they carry and swing upwardly with them such of the drops 31 of the signaling units in the several rows as have been actuated into signal-displaying position, swinging them upwardly sufficiently to cause the latching tongue 31^a (see Figure 4) to become engaged and latched by the armature 29, the latter acting under the action of spring 38. The pivotal mounting of the restoring members is preferably relatively loose so that the members are restored to their normal horizontal position (as shown in Figure 2) by their own weight and hence by gravity.

The several vertically displaced restoring bars or members 46, 47, etc. are connected as by links 50 (Figures 6 and 2) so as to be swung in unison. One of the restoring members, preferably the lowermost and hence member 46 (Figures 6 and 2) is provided with a depending plate 51 which acts as a cam follower with respect to the cam portion 42^c of the push button member 42 (Figure 2). With the push button 41 held in its outermost position by spring 46 cam follower 51 and hence the restoring member or members are permitted to assume their normal or lowermost position as shown in Figure 2. However, when the push button 41 is pressed inwardly (to the right, as in Figure 2) member 42, which is prevented from rotating by the coaction of the portion 42^a with the rectangular guiding hole 43 in the supporting bracket 44 (see Figure 5), likewise is moved to the right and cam follower 51 and hence the restoring member are raised and swung upwardly due to the action of the cam portion 42^c of member 42, thus restoring any actuated drop or drops to normal non-indicating position.

Release of the button 41 permits the spring 46 to return the member 42 and hence the button 41 to their normal left-hand position (see Figure 2) the cam 42^c permitting the restoring members to reassume their normal horizontal positions as shown in Figure 2.

The coaction of the spring 46 with the bracket portion 44^a and the coaction of the cotter pin 45 with the bracket portion tend normally to hold the member 42 and the button 41 in substantially the position shown in Figure 2 so that the cover plate 36 may be easily attached or removed even though the push button 41 is coactively related to the cover 36 itself.

Referring to Figure 4, it will be noted that the insulating member 28 associated as part of the electromagnet 24 has projecting therethrough two connecting studs 52—53 which conveniently can take the form of headed brads force-fitted into suitable openings in the insulating plate 28; to the headed ends thereof the two terminals of the winding 25 of the magnet 24 are connected as by solder.

In assembling the unit or units to the back wall 16^a of the frame 16, these connectors 52—53 of each of the units are passed through suitably positioned relatively large openings 54 (Figure 2) in the back wall 16^a and thence force-fitted through suitable openings in a sheet 55 (Figures 2 and 3) of insulating material such as

fiber, pressboard, or the like, whereupon the conductors, generally indicated in Figure 2 at 56 and preferably insulated, are soldered to the connectors 52-53 and the superfluous lengths of the connectors cut off. The signaling units being securely fastened to the back wall 16^a of the frame 16, the sheet 55 of insulating material becomes held in place by the coaction of the connectors 52-53 with the soldered connections thereto of the wires of the insulated conductors 56. Moreover, the bared ends or connecting portions of the insulated conductors 56 are held out of contact with the frame 16 as are also the connectors 52-53 of the signaling units.

15 The conductors 56, depending in number upon the number of signaling units employed and in the manner of connection thereof, are led downwardly along the insulating member 55 (see Figure 2) whence they are carried toward the front 20 of the frame (to the left as viewed in Figure 2) where they are secured to binding posts or connecting devices mounted and arranged so as to be accessible from the front of the frame 16 or box 13 when the cover 36 is removed.

25 More specifically, I provide a relatively heavy and rigid sheet or plate 57 (Figures 2 and 7) of insulating material, such as fiber, pressboard, hard rubber, or the like, carrying a suitable number of connecting devices 58 which may be of any 30 suitable construction and which in number correspond to the number of electrical connections which the number of signaling units employed require. An illustrative construction for the devices 58 is shown in Figures 2 and 7; they may, 35 for example, comprise a sheet metal U-shaped member 58^a having ears 58^b and 58^c that pass through suitable openings in the insulating plate 57 whence they are bent over (see Figure 2) to hold the member 58^a in place; the latter is 40 threaded to receive a binding screw 58^d, the latter extending into a suitable opening in the insulating plate 57.

The conductors 56 that lead from the connecting members of the signaling units are brought 45 down to the right-hand or rear face of the panel or insulating plate 57 (see Figure 2) where they are soldered to a rearwardly exposed portion, such as one of the ears 58^b or 58^c, of the connecting device 58. These connections are made at 50 the factory prior to the installation of the apparatus in the wall and thus the conductors 59, only two of which are shown in Figure 2, from the cable or from the conduit that is brought into the box 13 through a knock-out 15, may 55 be brought to the lower front part of the assembled apparatus (lower left-hand part as seen in Figure 2) where the individual conductors or the conductors of the cable, if a cable is used, may be fanned out if desired and in any event 60 readily, quickly, and easily connected electrically by the connectors 58 to the respective signaling units.

The connector-carrying insulating plate 57 extends crosswise of the lower portion of the frame 65 16; its left-hand end is supported in place by a sheet metal yoke 60 (see Figure 3) which has two horizontally spaced flanges 60^a and 60^b, the former of which is secured to the back wall 16^a of the frame 16 as by the screws 61 and the latter of which has secured thereto as by the screws 62 (Figures 3 and 7) the left-hand end of the insulating plate 57. The screws 61 incidentally (see Figure 3) also hold the insulating sheet 55 in place against the back of the back wall 16^a.

70 75 The yoke 60 thus holds the left-hand end of

the insulating member 57 spaced forwardly away from the rear wall 16^a and is, moreover, so constructed as above described and as shown in the drawings, to resist any tendency for the part 57 to swing in its own plane.

The member 57 lies in a plane that is spaced rearwardly of the plane of the flanges 16^d and 16^e of the frame 16 and hence also rearwardly of the plane of the cover 36 (see Figures 2 and 3), thus to provide adequate space between the cover 10 36 (see Figure 2) and the insulating support 57 for bringing the numerous conductors 59 around in front and to make the connections thereof to the binding posts 58.

The right-hand end of the insulating plate 57 15 is received in a vertically extending slot 16^k (see Figures 8 and 3) provided in the lower forward portion of the side wall 16^c of the frame 16 and spaced rearwardly of the flange 16^e (see Figure 8). Thus, the right-hand end of the connector 20 plate or panel 57 is held against movement in a direction transversely of its plane.

Where the apparatus is to be operated from a source of low voltage alternating current such as commercial 60-cycle alternating current, the 25 energization of any one signal unit, as by closing the circuit between its electromagnet and the source by means of a push button positioned at any remote point, achieves not only the release of the signal-carrying drop 31 into the signal- 30 displaying position above described, but also an audible signal or buzzing sound which thus audibly signals the fact that a drop on the annunciator has just been actuated.

This audible signal is achieved by the coaction 35 of the electromagnet 24 with the spring-opposed armature 29 (Figure 4) which vibrates synchronously with the frequency of the alternating current employed, its vibrating contact with its coacting parts achieving an appropriate 40 audible signal.

However, in case the source of energy from which the signaling devices are actuated is a direct current source or a source otherwise not adapted to cause the pivoted armatures to vibrate audibly, I prefer to provide a separate 45 audible signaling device which is common to all of the signaling units and which is connected in any suitable way (not shown) so that the actuation of any one signaling unit 21, 22, etc. at the 50 same time also actuates the audible signaling device; the latter preferably takes the form of a buzzer generally indicated in Figure 7 at 63.

The buzzer 63 includes a magnetic core 64 about which is wound the energizing winding 65 55 and coacting with the core 64 is a vibratable armature 66 with which coacts any suitable circuit-interrupting arrangement whereby the attraction of the armature 66 and its movement in a downward direction as viewed in Figure 7 60 interrupts the circuit of the winding 65 to cause a spring 67 to move the armature 66 upwardly and thus complete the circuit again, thus achieving a vibrating of the armature 66 at an audio frequency rate.

The buzzer or equivalent audible signaling device is carried by the sheet metal yoke 60 (Figure 3), the yoke 60 having a horizontally extending arm 60^c (Figure 7) that extends virtually across the bottom of the space between the left-hand 70 wall 16^b of the frame 16 and the yoke 60.

The buzzer 63 is secured to the arm 60^c (Figure 7) by a screw 68 which passes through a suitable opening in the arm 60^c and is threaded into the lower end of the core 64.

The conductors (not shown) that lead from the buzzer 63 may be brought in back of the connecting panel 57 to be connected to connecting devices 58 as by soldering to the ears thereof exposed to the rear of the insulating plate 57.

Thus, all of the internal connections of the apparatus may be made in the factory and the conductors brought to connecting terminals or binding posts 58 on the connecting panel 57 and 10 the latter may bear suitable identifying indicia for the numerous connecting devices 58 that it carries, identifying the connectors 58 with their respective signaling units.

The box 13 (Figures 2 and 3) may be installed 15 in the course of construction of the wall or building and the conduit led thereto through any desired knock-out 15. The cable or individual conductors that lead from the source of current or from the various push buttons or circuit-controlling device from which a signal is to be initiated 20 may be strung through the conduit and into the box 13 at any suitable or appropriate stage of the building construction work. The frame 16 with the signaling units and restoring mechanism, 25 forming a unit by themselves all wired up internally as above described, may then be installed and this is preferably done after the wall has been plastered or otherwise finished, and the connections of the conductors 59 (Figure 2) made to 30 the binding posts 58 on the front of the connecting panel 57, and the entire electrical installation tested and completed. The making of the electrical connections and the testing will be seen to be easily and quickly carried on, particularly since 35 the connecting terminals 58 are not only faced toward the open end of the box 13, but are also positioned toward the front thereof where they are readily accessible.

The cover plate 36 may then be mounted in 40 place, all as above described, it being recalled how conveniently and easily the frame 16 and hence the annunciator drops, likewise also the cover plate 36, are alined to the horizontal and the vertical.

45 In case of need for replacement or repair of any of the parts, or in case of a need for changing the connections, the mere removal of the cover plate 36 makes such parts readily accessible, it being in this connection particularly noted that 50 the restoring mechanism is virtually undisturbed by the removal of the cover plate 36 and that in any event no troublesome alinement of restoring devices with the annunciator drops need be resorted to.

55 If, for example, a new armature 29 (see Figure 4) has to be substituted for an old one, the up-standing arms 23^c and 23^d are simply sprung apart, the old armature taken out and a new one substituted.

60 It will thus be seen that there has been provided in this invention an apparatus in which the various objects above noted, together with many thoroughly practical advantages, are successfully achieved. It will be seen that the apparatus is 65 compact and is efficient and reliable in action, is neat in appearance and is readily and quickly installed, and that it, moreover, may be installed with a minimum of skill or labor.

As many possible embodiments may be made 70 in the above invention and as many changes might be made in the embodiment above set forth, it is to be understood that all matter hereinbefore set forth or shown in the accompanying drawing is to be interpreted as illustrative and 75 not in a limiting sense.

I claim:

1. In apparatus of the character described, in combination, a sheet metal frame having an aperture therein, an electromagnetic signaling device having a terminal and having projecting therefrom 5 a stud-like conductive member in electrical connection with said terminal of said device, said stud being of smaller cross-section than the aperture in said frame, a sheet of insulating material secured to said frame and extending over the 10 aperture therein, said stud passing through said insulating material and said device resting against said frame, an extraneous conductor, and means securing said conductor to said stud and acting to prevent retrograde movement of said 15 stud, whereby said device is secured in position.

2. In apparatus of the character described, in combination, a support including a sheet of insulating material, a signaling device having projecting therefrom 20 a metallic stud-like member in electrical connection with a terminal of said device, said stud-like member passing through said sheet of insulating material, and means in mechanical connection with said stud-like member for connecting thereto an extraneous electrical 25 conductor, said means engaging said sheet and preventing retrograde movement of said member through said sheet and thereby holding said device to said sheet support.

3. In apparatus of the character described, in 30 combination, a support including a sheet of insulating material having a plurality of apertures therein, a plurality of signaling devices, each having a terminal and having projecting therefrom 35 a metallic stud-like member in electrical connection with said terminal of said device, said stud-like members passing respectively through said apertures of said sheet of insulating material, means carried by said support and forming a panel having a plurality of binding posts, a 40 plurality of extraneous conductors respectively connected to said plurality of binding posts, and means securing each conductor to a projecting stud-like member, said means engaging a face of 45 said sheet support and being larger than the apertures through which said stud-like member passes, thereby acting to prevent retrograde movement of the member.

4. In apparatus of the character described, in combination, a box dimensioned to be seated in a 50 recess in a wall, a frame removably received within said box, a plurality of signaling units carried by said frame, said units having terminal connectors exposed rearwardly of said frame, a panel of insulating material exposed forwardly 55 of said frame and having a plurality of binding posts on the front face thereof, a plurality of conductors permanently interconnecting said binding posts and said terminal connectors, said box having a knock-out through which conductors 60 may be introduced into the box and connected to said binding posts.

5. In apparatus of the character described, in combination, a box dimensioned to be set into a recess in a wall and having means for securing it 65 in position and means for leading a conductor through a wall thereof, a frame having plane end portions dimensioned to extend beyond opposed sides of said box and to rest against the face of said wall, thereby to aline said frame with 70 respect to said wall face, said frame supporting interiorly of said box a plurality of electro-responsive visual signaling devices with means for actuating them into signal-displaying position and means for restoring to non-displaying posi- 75

tion, means for securing said frame to said box, said securing means being operative throughout a plurality of positions of said frame relative to said box whereby said frame with its visual signaling devices may be alined to a true horizontal position irrespective of misalignment of said box in said recess, and said securing means holding said plane end portions against said wall face, a cover plate peripherally flanged to engage said 10 wall face and dimensioned to encompass within its flange the area of said recess in the wall and also said opposed frame end portions, said cover plate having window means through which said signaling devices, when in signal-displaying positions, are visible, and means securing said cover plate to said frame and operative always to aline said window means with said signaling devices.

6. In apparatus of the character described, in combination, a box dimensioned to be set into a 20 recess in a wall and having means for securing it in position and means for leading a conductor through a wall thereof, a frame having plane end portions dimensioned to extend beyond opposed sides of said box and to rest against the face of 25 said wall, thereby to aline said frame with respect to said wall face, said frame supporting interiorly of said box a plurality of electro-responsive visual signaling devices each capable of assuming either a signal-displaying condition or a non-displaying 30 condition, said frame carrying means for activating said signaling devices into signal-displaying condition and carrying also means including a forwardly projecting reciprocable member, said frame having bearing means for slidably supporting the rear end of said member, means adjustably securing said frame to said box and capable of giving the former any one of a plurality of positions relative to the latter whereby 35 said signaling devices may be alined with respect to the horizontal independently of said box, a cover plate of an area sufficient to close over said recess and said frame end portions and having aperture means through which said signaling devices are visible when activated into signal-dis- 40 playing conditions, said cover plate having bearing means for slidably supporting the forward end of said reciprocable member, the latter projecting through said cover plate, and means securing said cover plate to said frame in such 45 relationship that said aperture means is alined with said signaling devices and said bearing means in the cover plate is alined with respect to the bearing means in said frame.

7. A construction as claimed in claim 6 in which said frame bearing means comprises a lug with an aperture therein in which the rear end portion of said reciprocable member is slidably received, said end portion having thereabout a spring abutting against said lug for biasing said reciprocable member forwardly of said frame and hence for normally causing said forward portion to project forwardly through said cover plate for manual actuation.

8. A sub-assembly for an annunciator construc-

tion of the character described, comprising, in combination, a sheet metal frame substantially U-shaped in horizontal cross-section and hence having a rear wall portion and two side wall portions, a plurality of signaling units each comprising a movable signal member with means for holding it in non-signal-displaying position and electromagnetic means for effecting release thereof by said holding means, means supporting said signaling units from said frame, and means for restoring said signal members to non-signal-dis- 5 playing position comprising a U-shaped member, means pivotally connecting the arms of said U-shaped member to the respective side wall portions of said frame whereby the cross-bar 10 portion of said U-shaped member is given a path of movement about the axis of said pivotal connection to restore said signal members from displaying position to non-displaying position, and means for actuating said U-shaped member about 15 said axis.

9. A sub-assembly for an annunciator construction of the character described, comprising, in combination, a substantially U-shaped sheet metal frame hence having a rear wall portion 25 and two arm-like portions, the latter having means for mounting the frame to a suitable support, a plurality of electro-responsive signaling devices carried by said frame in the space between said two arm-like portions and said rear 30 wall portion, the latter having a plurality of apertures therein, said signaling devices having electrical terminals extending through said apertures and hence exposed to the rear of said rear wall portion, a connecting panel having connect- 35 ing terminals, means securing said panel to said frame and positioning it so that the connecting terminals thereof are accessible from a side of said frame other than the rear of said frame, and electrical conductors permanently connecting 40 said rearwardly exposed terminals to respective terminals of said connecting panel.

10. In annunciator construction, in combination, a U-shaped sheet metal frame whose rear wall portion and two arm-like portions extend 45 into a box, a plate extending parallel to said rear wall portion to close over said box, means securing said plate to said two arm portions, said plate having a window and an aperture in an area juxtaposed to said rear wall portion, a movable 50 signal member having means for holding it away from said window and electromagnetic means for releasing said holding means, all carried by said frame and to the rear of said window, a spring- 55 opposed reciprocable member projecting through said aperture in said plate and slidably guided thereby, movable means mounted in the space between said plate and said rear wall portion for restoring said signal member to a position to be again held by said holding means, and means 60 whereby movement of said reciprocable member actuates said movable means.

CHRISTIAN MILLER.
